(57) **CLAIM**

We claim the ornamental design for a light-emitting diode with refracting lens, as shown and described.

DESCRIPTION

FIG. 1 is a front perspective view of a light-emitting diode with refracting lens, showing the claimed new design; FIG. 2 is a bottom perspective view of the light-emitting diode with refracting lens shown in FIG. 1; FIG. 3 is a front elevation view of the light-emitting diode with refracting lens shown in FIG. 1; FIG. 4 is a rear elevation view of the light-emitting diode with refracting lens shown in FIG. 1; FIG. 5 is a left side elevation view of the light-emitting diode with refracting lens shown in FIG. 1; FIG. 6 is a right side elevation view of the light-emitting diode with refracting lens shown in FIG. 1; FIG. 7 is a top plan view of the light-emitting diode with refracting lens shown in FIG. 1; and, FIG. 8 is a bottom plan view of the light-emitting diode with refracting lens shown in FIG. 1.
